UNITED STATES PATENT OFFICE.

BANCROFT G. BRAINE, OF MONTCLAIR, NEW JERSEY, ASSIGNOR TO THE RAIL JOINT COMPANY, OF NEW YORK, N. Y., A CORPORATION OF NEW YORK.

ADJUSTABLE RAIL-JOINT BAR.

1,361,818.

Specification of Letters Patent. Patented Dec. 14, 1920.

Application filed September 24, 1920. Serial No. 412,558.

To all whom it may concern:

Be it known that I, BANCROFT G. BRAINE, a citizen of the United States, residing at Montclair, in the county of Essex and State 5 of New Jersey, have invented certain new and useful Improvements in Adjustable Rail-Joint Bars, of which the following is a specification.

This invention relates to rail joint bars, 10 particularly of the continuous type, and has special reference to improvement therein for adapting a joint bar of given section to fit rail bases of different depth or thickness.

Owing to the variations in the cross sec- 15 tional dimensions of the bases of rails of different types and weight, but having the same depth of fishing space, it is proposed, in order to utilize the same fishing member of the given bar section, to provide a novel 20 form of base construction, whereby the extreme range in the bull-doing operation will be greatly increased to thus permit of the base being given a final set within comparatively wide limits to adapt the same to 25 different thicknesses of rail base, and also to slight variations in the slope of the flange surface of the rail.

By providing a construction that enables 30 the range of the bull-doing operation to be increased many joints may be obtained with different bases while the other features of the bar remain unchanged, thereby greatly simplifying and economizing rolling operations by reducing the number of sections in 35 the rolls to a minimum.

Heretofore, it has been the practice to roll 40 the base of continuous joint bars in such a manner as to necessitate different passes in the roll to obtain the varying heights of the 45 strut member or that portion which connects the flange of the bar to the base. After the sections are rolled in accordance with this practice, the joint bar is bull-dozed to fit the base of the particular rail. The 50 present invention, however, involves a distinct departure from that practice in the respect that it is proposed to make the conformation of the strut portion and the toe such as to permit of displacing the base of the rail in the bull-doing operation to a greater extent than heretofore possible and also to place the spiking toe in proper plane with reference to the base of the bar, thereby permitting the adjustment of the base part

of the bar to a particular thickness of rail 55 base.

Aside from the foregoing general objects, other objects will appear as the description of the invention proceeds, and by reference to the accompanying drawings it will be 60 seen that:

Figure 1 is a cross sectional view of the continuous joint bar as it emerges from the final roll pass of the mill.

Fig. 2 is a cross sectional view of the bar 65 of Fig. 1 after the bull-doing operation, applied to a rail section: the dotted lines indicating a rail of smaller section and the bar adjusted thereto.

Fig. 3 is a view of a modification showing 70 a form of the invention which is a practical form for the rolling operation.

Figs. 4 and 5 respectively, are views showing variations of forms which may be adopted in embodying the improvement in the 75 base portion of a base supporting type of rail joint bar.

Similar reference numerals designate cor- 80 responding parts throughout the several figures of the drawings.

The desirability of adapting rolled joint 85 bars of standard design to meet different rail sections, by bull-doing or equivalent operations, has the well known advantage of utilizing a special or particular bar to meet 90 different rail sections without the necessity of providing separate and expensive sets of rolls. And it is primarily the object of the present invention to further increase the 95 range of utility of joint bar sections produced by a standard set of rolls, by definitely sub-dividing the base of the bar into an inwardly extending base portion and an outwardly extending spiking toe, both merging into a strut member and separately hinging thereon to permit of the adjustment of both to suit the particular rail to be fitted.

By reference to the accompanying drawings it will be seen that the continuous joint 100 bar C includes the upright fishing member 1, head 2, and foot flange 3, which terminates in the upright strut portion 4, connecting the base member 6, and spiking toe 5.

As previously pointed out, the distinctive 105 feature of the invention is the provision of a bar having a relatively adjustable base which conveniently permits of its being

- adapted to fit rails having different thicknesses of base. And, to permit of the adjustment of the base member and of the toe member by bull-doing or otherwise, without disturbing the position of the strut member or any other part of the bar, a compensating groove 7 is channeled at the bottom of the strut member (in the rolling operation) between the base member and the toe member.
- 10 The depth of this groove or channel corresponds to the range of adjustment intended for the base member and for the toe member, and, as shown in Fig. 2, provides an attenuation forming a hinging neck 8 between the base member and the strut, and a hinging neck 9 between the said toe member and the strut. By focusing the bending movement of the said members 5 and 6 at the hinging points or necks 8 and 9, each of such members
- 15 can be moved upwardly and outwardly from such points to bring them into final rail and tie engaging position without movement of the strut member or of the foot flange of the bar connecting therewith.
- 20 By reference to Fig. 2, it will be seen that the full line position of the base member and toe member of the bar shows the relative position of these members when the bar is fitted to a rail having a relatively thick base,
- 25 while the dotted lines in this figure show the position of the base and toe when they are pressed upwardly and outwardly at their hinging necks to fit a rail having a base of relatively shallow depth. In connection with
- 30 the range of movement of the base and toe members it will be noted that the same may be moved from their initial positions, that is, the positions they assume when leaving the final roll pass, to a relatively horizontal
- 35 position, parallel with the rail base, until the channel or groove 7 is obliterated. Between these relative limits it will be apparent that many thicknesses of rail base may be accommodated, thus permitting the
- 40 use of the other standard features of the bar without change.
- 45 To illustrate the range of modification that may be resorted to in carrying out the invention, reference is made to Figs. 3, 4 and 5 of the drawings. In all of these modifications a somewhat different relation of the base and toe members to the so-called strut member is shown. However, a primary feature of the invention resides in providing a reentrant
- 50 channel or groove designated by the numeral 7, between the base member and the toe member to locate a hinging point for these two members. In the form of construction shown in Figs. 1 and 2 of the drawings, the
- 55 groove or reentrant channel 7 is shown as being located in the base of the strut, and while that form of the invention has its practical advantages, it will be observed that the construction shown in Fig. 3 of the drawings
- 60 also permits the adjustment of the base mem-

ber and of the toe member, to adapt them to the tie seating surface and to the particular rail base, without disturbing the position of the flange of the bar. Furthermore, in the form shown in Fig. 3, the base member of the bar and the toe member are so related, initially, as to make a very desirable rolling proposition, since the said members in the position shown, may readily be formed in the passes of the rolls and subsequently bull-

70 dozed to the desired positions as indicated by the full and dotted lines. Referring to the structural characteristics of the modification shown in Fig. 3, the so-called strut member 4, is continued directly into the base member and the toe member offset laterally from the part of the bar where the flange merges into the so-called strut member. This relation of the parts produces a well defined reentrant groove or channel designated by the numeral 80 7^a and which serves to provide the hinge point above referred to for both the base member and the toe member.

Except for the toe member joining the so-called strut member at an intermediate 90 point, the modification of Fig. 4 embodies the same structural and functional features as the construction shown in Fig. 3.

The modification shown in Fig. 5 is merely a reversal of the idea presented in Figs. 3 and 4, viz: in having the so-called strut member extending outwardly into the toe member and the base member joining the so-called strut member at the inner side thereof below the flange. In the said modification of Fig. 5, a reentrant groove or channel 7^a, is formed in the metal between the base member and toe member to provide the hinging point referred to.

While special emphasis has been placed on 105 the utility of the invention in its application to different weights of rail having the same fishing space, it will of course be understood that the invention is an improvement in the base part of a joint of the rail base supporting type and is applicable to step or compromise joints.

Without further description it is thought that the many features and advantages of the invention will be readily apparent to 115 those skilled in the art and it will, of course, be understood that changes in the form, proportion and minor details of construction may be resorted to in the spirit of the invention and scope of the appended claims.

I claim:

1. A rail joint bar having adjustable base and toe members.
2. A rail joint bar having separately adjustable base and toe members.
3. A rail joint bar having a fixed fishing member and strut, and adjustable base and toe members connecting with the strut.
4. A rail joint bar having a fixed fishing member and strut, and an adjustable base

- member having an integral hinging connection with the strut.
5. A rail joint bar having a fixed fishing member and strut, and adjustable base and toe members, each connecting with the strut by an attenuated neck.
6. A rail joint bar having a fixed fishing member and strut, and adjustable base and toe members connecting with the strut, said 10 bar having a groove in the base of the strut between the base and toe members producing hinging points for the latter.
7. A rail joint bar having a body of metal projecting from its fishing member, two 15 flange members projecting respectively from

opposite sides of said body of metal, and a depression in the base of said body of metal forming attenuations adjacent the point of union between the said flange members.

8. A rail joint bar having a base member, a toe member and a reentrant groove or channel formed between said two members to produce hinging points for the same.

In testimony whereof I hereunto affix my signature in the presence of two witnesses. 25

BANCROFT G. BRAINE.
